UNITED STATES PATENT OFFICE.

EDWARD E. CLEMENT, OF WASHINGTON, DISTRICT OF COLUMBIA.

ELECTRICAL SELECTIVE SWITCH.

1,105,491.

Specification of Letters Patent. Patented July 28, 1914.

Original application filed April 12, 1906, Serial No. 311,388. Divided and this application filed March 16, 1912. Serial No. 684,368.

To all whom it may concern:

Be it known that I, EDWARD E. CLEMENT, a citizen of the United States, residing at Washington, in the District of Columbia, have invented certain new and useful Improvements in Electrical Selective Switches, of which the following is a specification, reference being had therein to the accompanying drawing:

10 My invention relates to electrical switches, and has for its object the improvement of said switches in certain particulars which will hereinafter appear.

The present application is a division of 15 my prior application No. 311,388, filed April 12, 1906, in which a system is described and claimed, but not the switch structure.

I claim the switch structure herein, without regard to the system in which it is used.

20 My invention is illustrated in the accompanying drawings in which—

Figure 1 is a side view of the switch, showing a single bank of contacts and related parts, which in practice may be multiplied 25 if desired. Fig. 2 is a cross section through a single bank and related parts. Fig. 3 is a plan view. Fig. 4 is a diagram of the circuit with which the switch may be usefully employed.

30 In Figs. 1 to 3 I have shown a single switch mounted in a frame, but obviously in practice I may employ any desired number of said switches. Referring to these figures, S is the switch, having a base-plate s, carrying vertical standards s', connected at the top by a spider s", having three arms secured to the standards and a central bearing for the upper end of the vertical spindle s". This spindle as shown has its ends provided with depressions, which receive and turn upon the points of center screws, s", s", both screws being adjustable and provided with locking nuts.

Supported within the frame upon brackets s", is the circular contact-bank s', comprising upper and lower plates s" and s", connected by screws s", and clamping between them the circular series of contacts with rings of interposed insulation. These springs are 45 in sets, each set appertaining to one particular line, and comprising the following: An upper individual spring s", for testing purposes; a lower trunk ring s", a pair of talking circuit line-springs s", s"; a pair of

trunk talking circuit springs s", s", and a pair of line-number-signal springs, s" and s".

Within the ring of contacts the spindle s" is provided with a gain or annular notch s", in which lie the edges of a pair of plates, s" and s", screwed to the iron head of an electromagnet s", which is wound on a brass or iron tube surrounding the spindle. The spindle itself forms the core of this magnet, and passes through an opening s" in the 60 armature s" thereof, which is pivoted to the iron jacket of the magnet at s", and carries the bell-crank lever-arm s", whose upper end extends through a slot in the bottom of the tube s" and a registering slot 70 in the plug s" of insulating material. As the armature is pulled up it throws out the plug s" so that it passes between any pair of springs s", s", to which it is opposite. At the same time, it withdraws the pin s" 75 from its normal resting place in a notch in the disk s", which is rigidly secured on the spindle s".

In order to maintain the armature down and the plug s" retracted, as well as to furnish means for testing the line-contacts s", I provide the strong spring s" secured at its lower end at the angle of the bell-crank armature lever, and steadied at its upper end by being perforated so that the plug 80 tube passes through it. A companion spring s" constitutes a sliding contact which is in constant engagement with the trunk ring, s", and these two springs s" and s" are connected to two separate windings of the magnet s", the inner ends of both of which are grounded on the spindle. The first winding, being connected with the spring s" takes current when that spring comes on a calling contact. This pulls up the armature, stops the rotation of the magnet, and at the same time throws out the plug s" 85 between the springs, s", s", of the set corresponding to the calling line, connecting the contacts s", s" of the trunk thereto. 90 The trunk contact s" takes current at this time controlled by one of the trunk relays, and hence as long as that trunk relay remains active current passes through the ring s", the spring s", and the second 95 winding of the magnet to the spindle and ground. The trunk relay is controlled by the calling subscriber, and as it becomes ac-

tive the subscriber's line cut-off relay is also energized, so that the line spring s^{11} becomes dead, and at the same time the jacks of the subscriber on the telephone switchboard have their potentials raised in order that they may test busy.

Referring to Fig. 4 a subscriber's line is shown at 1-2, equipped with the ordinary substation telephone set, and in addition thereto with a switch K, a thermostat T and a burglar alarm B. The line terminates on the contacts of a cut-off relay at the central office, through which the two sides of the line are normally connected to signaling relays M and M' respectively. When the line is grounded the relay M' becomes energized and raises the potential on the test contact (or contacts where several switch banks in multiple are employed). When the subscriber's receiver is removed from the hook however for ordinary telephonic conversation, both relays M and M' are energized, and the switch S remains unaffected. R^o and R' are trunk relays in the battery circuit at the central office, and R⁴ is a signaling relay at a signal receiving station.

It is to be understood that while the description and illustration herein are confined to a single unit switch, this unit may be multiplied into groups or group units, having a common driving shaft s^3 . For example, in serving a group of one hundred subscribers' lines, it may be desirable or necessary to have more than one trunk and more than one switch, the lines being multiplied into the banks of the several switches. In such case, the construction of Figs. 2 and 5 would be repeated, sets of banks and operating magnets being located vertically over each other, so that the common spindle or shaft s^3 would pass axially through all of them. With such an arrangement, the test wipers s^{26} of the several switches would all be driven around simultaneously, and in order to prevent interference, whereby two trunks might become connected to the same line, the collars s^{29} should be set with their openings to receive the pins s^{28} angularly displaced from each other. The effect of this will be to have the wipers s^{26} of the several switches follow each other over the vertically recurring multiples of the same line, so that the same line would be tested as many times in the course of one rotation of the spindle s^3 as there are switch units driven by said spindle.

It should also be observed in closing that the usefulness of this switch is not confined to a fire or police system, but that it may be employed wherever so-called "line finders" or "testing selectors" are required.

Having thus described my invention what I claim and desire to secure by Letters Patent is:-

1. An automatic selector switch comprising

ing in combination a row of contacts, an operating member for the same, having a normally continued regular movement along the said row of contacts, and selectively controlled actuating means for the operating member adapted automatically to cause the operating member to effect circuit connections through any determined one of said row of contacts.

2. A selector switch comprising in combination a plurality of groups of contacts the contacts of which are adapted to coöperate with each other to effect circuit connections, an operating member adapted to be moved from group to group of said contacts and to effect the coöperation of the same, and selectively controlled actuating means for the operating member adapted to cause the operating member to effect the coöperation of the contacts of any determined one of said groups after said group has been reached by the operating member in its movement.

3. An automatic selector switch comprising a row of contacts, a coöperating circuit closing member adapted to effect the closure of circuits through said contacts and to be moved past said contacts normally disengaged therefrom, and actuating means for the operating member adapted automatically to cause the operating member to effect circuit connections through any determined one of said row of contacts.

4. An automatic selector switch comprising in combination, a plurality of groups of terminal contacts, a plug member adapted to effect circuits through the contacts of said groups, and adapted to be moved automatically past said groups of contacts, and selectively controlled actuating means adapted automatically to operate the plug member to effect circuit connections through any determined one of said groups of contacts.

5. An automatic selector switch comprising in combination, a row of contacts, an operating member for the same adapted to be moved along said row, electromagnetic actuating means for causing the operating member to effect circuit connections through any desired contact of the row, and a test wiper moving with the operating member along the row of contacts, and controlling the circuit of the said actuating means.

6. An automatic selector switch comprising a circular series of contacts, a circuit closing member adapted to effect the closing of a circuit through any individual contact, means for rotating said member past said contacts, and selectively controlled electromagnetic actuating means adapted to move said member into operative engagement with any determined contact of said series.

7. An automatic selector switch comprising a circular series of contacts, a radially movable circuit closing member adapted to effect the closing of a circuit through any

individual contact, means for rotating said member past said contacts, and selectively controlled electromagnetic actuating means adapted to move said member into operative engagement with any determined contact of said series.

8. An automatic selector switch comprising a row of contacts, a circuit closing member adapted to effect a circuit through any predetermined one of said contacts movable into and out of engagement therewith, and adapted for movement past said row, electromagnetic actuating means for moving said circuit closing member into the engagement aforesaid, and circuit connections therefor controlled through individual contacts of said row.

9. An automatic selector switch comprising a row of contacts, a circuit closing member adapted to effect a circuit through any predetermined one of said contacts movable into and out of engagement therewith, and adapted for movement past said row, electromagnetic actuating means for moving said circuit closing member into the engagement aforesaid, said means having two separate windings, circuit connections to one of said windings controlled through the contacts of the row for effecting initial operation of said circuit closing member, and means whereby the second winding may be energized to hold the circuit closing member in actuated position.

10. An automatic selector switch comprising a row of contacts, a circuit closing member adapted to effect a circuit through any predetermined one of said contacts movable into and out of engagement therewith, and adapted for movement past said row, electromagnetic actuating means for moving said circuit closing member into the engagement aforesaid, said means having two separate windings, through the energization of either of which said circuit closing member may be moved to effect the closure of a circuit through any predetermined one of said contacts.

11. An automatic selector switch comprising a row of contacts, a movable supporting member, a circuit closing member normally clutched thereto and movable thereby along said row of contacts, said circuit closing member being adapted to effect circuit connections through any predetermined one of said contacts, and electromagnetic actuating means for said circuit closing member adapted simultaneously to unclutch said member from its supporting part and move the same into operative engagement with the said contacts.

12. An automatic selector switch comprising a row of contacts, a test wiper, a support for the same adapted to move said wiper over the contacts successively, a clutch normally connecting the wiper with said

support, and an electromagnet controlling said clutch and having an energizing circuit controlled through said test wiper.

13. An automatic selector switch comprising a row of contacts, a spring test wiper, a movable member adapted to support said wiper and move the same along said contacts, an electromagnet controlling the movement of said wiper by said support and having an armature biased to retracted position by the spring of said wiper.

14. A selector switch comprising the following instrumentalities: a circular series of line terminals, a central spindle, an electromagnet axially supported on said spindle to turn thereon, an armature for said magnet, a plug carried thereon and adapted to reciprocate in a radial direction with respect to the spindle, and a connection between the armature and said plug whereby the plug is thrown out to effect a change in the terminal connections when the armature is attracted.

15. A selector switch comprising a circular series of contacts, a central spindle constantly driven, an electromagnet carrying a radial reciprocating plug and itself axially journaled on the spindle, an armature for said magnet having a lever controlling the movement of the plug, and a clutch for connecting the magnet to the spindle also controlled by said armature, whereby upon energization of the magnet the same will be disconnected from the spindle and its plug will be thrown out to engage the opposite contacts.

16. A selector switch comprising the following instrumentalities: a circular series of contacts, a central spindle of magnetic material, an electromagnet journaled upon said spindle and carrying a radial reciprocating plug, an armature for said magnet having a lever connection with said plug, and a clutch connection with the spindle, said spindle forming the core of the magnet, and the armature serving when attracted to mechanically disconnect the latter so that it will remain stationary and at the same time its plug will be projected into engagement with the opposite contacts.

17. A selector switch comprising the following instrumentalities: a bank containing a plurality of sets of fixed or passive contacts, a driven spindle centered with respect to said contacts, a test wiper or active contact carried on said spindle, a plug on the spindle in fixed angular relation to the test wiper, and an electromagnet controlling said plug, and having its windings controlled through the test wiper.

18. A selector switch comprising the following instrumentalities: a bank containing a plurality of sets of fixed or passive contacts, each set comprising a plurality of switching contacts, and a test contact, a

driven spindle centered with respect to the bank contacts, a plug rotating with said spindle and adapted to coöperate with the switching contacts of the respective sets, a test wiper or active contact coöperating with the test contacts in the bank, and an electromagnet controlling said plug and having its windings connected to said test wiper so as to be energized by current supplied there-

10 through.

19. A selector switch comprising the following instrumentalities: a bank of contacts containing a plurality of fixed or passive sets, each set appertaining to a determinate circuit possible of selection by the switch, and each set consisting of switching contacts adapted to be spread by the plug, a test contact, and two control contacts, a driven spindle centered with regard to the bank, a reciprocating plug carried on said spindle, an armature lever controlling said plug, an electromagnet controlling said armature lever, a test wiper and a pair of control wipers connected to different portions of the 25 windings of said electromagnet, and local circuit connection for said control contacts.

20. A selector switch comprising the following instrumentalities: a curved bank of

fixed or passive contacts divided into sets, each set used together and with a particular circuit to be selected by the switch, a pair of switching contacts in each set and a pair of common coöperating contacts extending into all the sets, with test and control contacts also in each set, a driven spindle centered with regard to the bank, a radial reciprocating plug carried on the spindle and adapted to coöperate with the switching contacts, an electromagnet, a bell crank armature and lever therefor, the end of said lever engaging said plug, test and control wipers connected to said electromagnet adapted to engage the test and control contacts in the bank, and circuit connections whereby a current from a live test contact will energize said magnet and cause the plug to be moved with respect to the spindle to engage with the switching contacts of the set in which the said live test contact is found.

In testimony whereof I affix my signature in presence of two witnesses.

EDWARD E. CLEMENT.
